UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Original application filed March 3, 1919, Serial No. 280,394. Divided and this application filed December 7, 1923. Serial No. 679,213.

My invention relates to mining apparatus.

An object of my invention is to provide an improved mining apparatus. Another object of my invention is to provide improved supplemental supporting means for a mining machine truck, and, more especially, such means adapted to use in unloading the mining machine on a bench or skids. A further object of my invention is to provide an improved mining apparatus of the general character described and claimed in my copending application Ser. No. 280,394, filed Mar. 3, 1919, of which this application is a division, having improved and simplified supplemental supporting means actuated in an improved and simplified manner. These and other objects and advantages of my improved construction will, however, herein-after more fully appear.

In the accompanying drawings I have shown for purposes of illustration one form which my invention may assume in practice.

In these drawings,—

Fig. 1 is a side elevation of a mining apparatus equipped with my improvement, the parts being shown in transport position.

Fig. 2 is a fragmentary view of Fig. 1, showing the parts in the position assumed during the process of unloading.

In this illustrative construction I have shown a mining machine truck, generally designated 1, having a longitudinally disposed frame 2 mounted on and extending beyond the front wheels of a set of truck wheels 3 which in turn are movable along a trackway 4 in a well known manner. As in usual construction the truck wheels 3 are driven from a mining machine, generally designated 5, herein of the flexibly fed, room and pillar, endless cutter chain type and carried on the truck, a gear 6 on the rear end of the mining machine meshing, when the machine is in transport position, with a gear 7 mounted on the rear end of the truck frame 2 and driving through mechanism (not shown) a transverse truck driving shaft 8 through chain and sprocket connections 9 and 10 with the truck wheels 3.

It will be observed that I have provided improved supplemental means for supporting the front end of the mining apparatus. As shown these means engage directly with the mine bottom and are preferably so lo-

cated relative to the front end of the truck frame 2 as thereby to provide a rigid support for the machine as the latter is moved longitudinally over the front end of the truck. More particularly, it will further be noted that the supporting means are directly actuated and controlled by the mining machine 5 through an improved and simplified construction and arrangement of parts. Referring more particularly to the drawings it will be observed that a member 11, herein in the form of a laterally projecting pin extending from the side of the machine 5 and movable with the latter, engages with an upstanding cam member 12 of improved form pivotally mounted at 13 beneath the frame 2 in such manner as to swing the cam member 12 about its pivot and thereby operating a pivoted rod 14. As shown, the downward limit of movement of this rod is established by a stop member 15 and the front end of this rod is pivotally connected at 16 to the upper end of a supporting member 17 pivoted at 18 beneath the front end of the frame 2 and having its lower end engageable with the mine bottom at a point between the sides of the frame 2 and in front of the track. In the form illustrated herein, the cam member 12 is provided with a plurality of cam surfaces 19 and 20, of which the surface 19 is adapted to be disposed above the level of the frame 2 when the support 17 is in its inoperative position as shown in Fig. 1. Thus it will be observed that by providing a suitable trough or hollowed out portion 21 between these surfaces 19 and 20, it is possible to actuate this cam member to raise and lower the support 17 as the machine is loaded or unloaded. Preferably, the support 17 is also adapted to use on the usual varying mine bottom by providing the same with a vertically adjustable portion or foot 22 adapted to be held in different positions relative thereto by a suitable bolt 23 receivable in apertures 24 in the support 17. Obviously, in the use of this form of my invention, a like arrangement of parts may be, and is herein understood to be, provided on each side of the truck.

In the operation of my improved mechanism it will be observed that it is possible to unload a room and pillar mining machine on a bench or on skids in a well known man-

ner without the necessity of jacking up the front end of the truck frame. In considering the operation of the mechanism let us remember that the machine in its movement 5 about the mine occupies the transport position on the truck as shown in Fig. 1 and that the supporting means is in its inoperative position. The truck is, as usual, brought into a room or up to a bench under its own power and stopped with the front wheels thereof closely adjacent the front end of the mine track and with the front end of the truck frame 2 extending beyond the end of the track in such manner as to bring the machine as close as possible to the bench or the skids before it is unloaded. As the machine is moved forward longitudinally of the truck frame 2, in any well known manner, and before the center of gravity of the machine 10 passes over the front axle, the pin 11 on the machine engages the cam surface 19 on the cam member 12 thereby swinging the latter about its pivot 13 causing the rod to move forward and the support to swing downwardly engaging the bottom of the mine. Obviously after the machine has thus been provided with stable supporting means the machine is free to continue its forward movement, the machine sliding from the 15 frame 2 onto the bench or skids. It is also obvious that when the machine is again loaded onto its truck the pin 11 will engage the cam surface 20 on the cam member 12 thereby raising the support 17 from the mine bottom.

While I have in this application specifically described one form which my invention may assume in practice, it will be understood that this form of the same is shown 20 for purposes of illustration and that the invention may be modified and embodied in various other forms without departing from its spirit or the scope of the appended claims.

What I claim as new and desire to secure 25 by Letters Patent is:

1. In a mining apparatus, a truck, a machine slideable longitudinally of said truck and having a laterally projecting actuating element, and supplemental truck supporting 30 means having a portion engageable by said laterally projecting element on said machine for actuation thereby.

2. In a mining apparatus, a truck, a machine slideable longitudinally of said truck, and supplemental truck supporting members having bell cranks operatively connected thereto and actuated by said machine.

3. In a mining apparatus, a truck, and supplemental supporting means for said truck pivoted thereon having an operating member engageable directly by an element on and projecting laterally from a mining machine movable over said truck.

4. In a mining apparatus, a truck, supplemental supporting means pivoted thereon

having a cam shaped operating member and a mining machine movable relative to said truck and having a laterally projecting operating element engageable with said operating member.

5. In a mining apparatus, a truck, pivoted supporting means thereon having a plurality of projecting cam surfaces movable therewith, and means reciprocable on said truck and when moved in different directions engageable with different cam surfaces to move said supporting means positively in opposite directions.

6. In a mining apparatus, a truck, supporting members pivoted thereon, an operating member for said members provided with a plurality of cam surfaces, and a mining machine movable relative to said truck and engageable with different surfaces during loading and unloading to move said operating member positively in opposite directions.

7. In a mining apparatus, a truck, a machine slideable longitudinally of said truck, and supplemental truck supporting members having a bell crank operatively connected thereto and movable in a vertical plane and actuated by said machine.

8. In a mining apparatus, a truck, a machine movable longitudinally thereof, supplemental truck supporting means for the front end of said truck, and actuating means therefor carried directly by and laterally projecting from said machine engageable with said means during the first stages of movement of said machine in one direction

9. In a mining machine, a truck, a machine movable longitudinally thereof, supplemental truck supporting means for the front end of said truck, and actuating means therefor carried directly by said machine engageable with said means during the first stages of a movement of said machine in one direction and the last stages of a movement of said machine in the opposite direction and moving the same positively into active and inactive positions.

10. In a mining apparatus, a truck, a machine slideable longitudinally of said truck, and supplemental supporting means having operating cam surfaces laterally offset from the path of and engageable with said machine and operative to prevent forward tilting of said truck.

11. In combination, a truck, a supplemental pivoted truck supporting means thereon, and means actuated by movement of a load on said truck for swinging said means into substantially upright operative position.

12. In combination, a truck, a pivoted truck supporting means thereon disposed in substantially upright operative position beneath the same, and actuating means therefor actuated upon movement of a load on said truck.

13. In combination, a truck, a pivoted

truck supporting means thereon movable into and out of a substantially upright operative position, and means for actuating the same movable longitudinally of said truck.

5 14. In a mining apparatus, a truck, a machine slideable longitudinally of said truck, and truck supporting members having oppositely disposed cam surfaces engaged by said machine to move said truck supporting members positively in opposite directions.

10 15. In a mining apparatus, a truck, a machine slideable longitudinally of said truck, and supplemental truck supporting means having a cam surface laterally offset from the path of and engaged by said machine.

15 16. In a mining apparatus, a wheeled truck, supplemental truck supporting means including a member disposed laterally with respect to the path of machine movement, and means movable with a machine on said truck engageable with said member and actuating the latter and said supporting means.

20 17. In a mining apparatus, a wheeled truck, supplemental truck supporting means including a cam laterally disposed with respect to the path of machine movement, and means movable with a machine on said truck engageable with said cam and actuating the latter and said supporting means.

25 18. In a mining apparatus, a wheeled truck, supplemental truck supporting means including a plurality of members disposed laterally with respect to the path of machine movement, and means movable with a machine on said truck engageable with said members and actuating the latter and said supporting means.

30 19. In a mining apparatus, a wheeled truck, supplemental truck supporting means including a plurality of members disposed outside of the sides of said truck, and means movable with a machine movable on said truck engageable with said members and actuating the latter and said supporting means.

35 20. In a mining apparatus, a wheeled truck, a mining machine movable thereon, truck supporting means including a member pivoted to the outside of one side of said truck, and means movable with the machine engageable with said member and actuating the latter and said supporting means.

40 21. In a mining apparatus, a wheeled truck, a mining machine movable thereon, truck supporting means including a plurality of members pivoted outside the opposite sides of said truck, and means movable with the machine engageable with said members and actuating the latter and said supporting means.

45 22. In a mining apparatus, a wheeled truck, a mining machine movable thereon, truck supporting means including movable means disposed outside the side of said truck and longitudinally spaced relative to the truck wheels, and means movable with the

machine engageable with said movable means and actuating the latter and said supporting means.

50 23. In a mining apparatus, a wheeled truck, truck supporting means including movable means disposed outside the side of said truck and a supporting member longitudinally spaced relative to the truck wheels, and means movable with a machine movable on said truck engageable with said movable means and actuating the latter and said supporting member.

55 24. In a mining apparatus, a wheeled truck, truck supporting means including means disposed outside the side of said truck and a supporting member in front of the front wheels, and means movable with a machine movable on said truck engageable with said means and actuating the latter and said supporting means.

60 25. In a mining apparatus, a wheeled truck adapted to receive a mining machine and permit movement of the same relative thereto, a mining machine thereon, and a supplemental truck support including an actuating member disposed laterally with respect to the path of machine movement and adapted to be actuated upon machine movement.

65 26. In a mining apparatus, a wheeled truck adapted to receive a mining machine and permit movement of the same relative thereto, a mining machine thereon, and a supplemental truck support including an actuating member disposed laterally with respect to the path of machine movement adapted to be actuated upon machine movement and a supporting member movable upon operation of said actuating member.

70 27. In a mining apparatus, a wheeled truck adapted to receive a mining machine, a mining machine thereon, and a supplemental truck support including an actuating member disposed laterally with respect to the path of machine movement and adapted to be reversely actuated upon reverse machine movements and a supporting member reversely movable upon reverse operation of said actuating member.

75 28. In a mining apparatus, a wheeled truck, and supplemental truck supporting means including pivoted actuating cams disposed outside opposite sides of said truck and adapted to be actuated upon reverse movement of the machine therefrom and supporting members likewise pivoted on said truck and movable upon movement of said actuating cams.

80 29. In a mining apparatus, a wheeled truck, supplemental truck supporting means including actuating members disposed outside the sides of said truck, a mining machine movable over said truck, and laterally projecting means movable with said machine and engageable with said actuating

means to operate the same and said supporting means reversely as said machine is moved reversely on said truck.

30. In a mining apparatus, a wheeled truck, supplemental truck supporting means including a member pivotally connected to the side of said truck and movable relative to said truck into engagement with a supporting surface at a point in front of the front wheels, and actuating means therefor comprising a member projecting into the path of movement of a body on said truck.
- 10 31. In a mining apparatus, a wheeled

truck, supplemental truck supporting means including a member pivotally connected to said truck and movable relative to said truck into engagement with a supporting surface at a point in front of the front wheels, and operative connections to said member disposed outside the truck whereby the latter may be controlled directly by a mining machine movable on said truck. ¹⁵

In testimony whereof I affix my signature.

MORRIS P. HOLMES.
